UNITED STATES PATENT OFFICE

148,025

DESIGN FOR A RAILWAY CAR BODY

Basil E. Jones, Flossmoor, Ill., assignor to The Pullman Company, Chicago, Ill., a corporation of Illinois

Application February 2, 1946, Serial No. 126,200

Term of patent 14 years

(Cl. D66—1)

To all whom it may concern:

Be it known that I, Basil E. Jones, a citizen of the United States, residing at Flossmoor, in the county of Cook and State of Illinois, have invented a new, original, and ornamental Design for Railway Car Body, of which the following is a specification, reference being had to the accompanying drawings, forming part thereof.

In the drawings—

Fig. 1 is a general perspective view of a compartment in the railway car body of my new design, and having certain portions broken away to afford a better illustration of the interior;

Fig. 2 is a horizontal mid-sectional view through Fig. 1;

Fig. 3 is a vertical transverse sectional view looking toward the left of the compartment shown in Fig. 1;

Fig. 4 is a vertical transverse sectional view but showing the side of the compartment opposite to that illustrated in Fig. 3;

Fig. 5 is a longitudinal mid-sectional view through the compartment as viewed in the direction of the door;

Fig. 6 is also a vertical longitudinal sectional view through the compartment and illustrating the window side thereof; and

Fig. 7 is a general perspective view of a conven-

tional railway car body of the type in which my new design is incorporated and having portions broken away to reveal the disposition of the compartment within the body and showing the supporting trucks in dotted lines.

The characteristic features of the present design reside in the compartment interior design shown in the drawings.

I claim:

The ornamental design for a railway car body, substantially as shown and described.

BASIL E. JONES.
